United States Patent Office.

S. H. BARNES, OF LANESBOROUGH, PENNSYLVANIA.

Letters Patent No. 93,037, dated July 27, 1869.

IMPROVEMENT IN WATER-WHEELS.

The Schedule referred to in these Letters Patent and making part of the same.

To all whom it may concern:

Be it known that I, S. H. BARNES, of Lanesborough, in the county of Susquehanna, and State of Pennsylvania, have invented a new and useful Improvement in Water-Wheels; and I do hereby declare that the following is a full, clear, and exact description thereof, which will enable others skilled in the art to make and use the same, reference being had to the accompanying drawings, forming part of this specification.

This invention relates to improvements in water-wheels, designed to provide certain improvements in the gates, calculated to facilitate the operation thereof, also the delivering of the water upon the buckets in a manner to have the best effect; also certain improvements in hanging the wheels; all as hereinafter more fully specified.

Figure 1 represents a top view, partly in plan and partly in horizontal section, and

Figure 2 represents a vertical section, taken on the line *x x* of fig. 1.

Similar letters of reference indicate corresponding parts.

A represents the buckets of a turbine wheel, of which *B* is the top of the case, and *C* the curved chutes, for directing the water to the said buckets.

E represents the gates, which are of plano-convex form, and supported at top and bottom in journals, whose axes are coincident with the axes of the convex portion thereof, and so arranged, with reference to the mouths of the chutes, that when turned into the position represented in red at *F*, the passage of the water to the buckets will be stopped.

The upper ends of these gates are provided with gear-wheels *G G*, geared with a large wheel, *H*, by which all the gates are opened and closed simultaneously, and the proper relative positions of the gates maintained.

In gearing these gates with the wheel *H*, it is important that they be so adjusted, that in opening they will turn against the points of the preceding chutes, as represented in fig. 1, by which they guide the water more directly to the buckets than when opening in the opposite direction. Yet the opposite direction may be available.

This arrangement of the buckets is also advantageous in cases when it is not required to apply the whole amount of water which the wheel is capable of taking, as they open equally from bottom to top, and thus deliver the lesser quantity equally in the buckets.

My improvement in suspending the wheel consists in the arrangement of a hollow convex block of wood, *I*, on the top of the curve, or other support, above the same, and the concave collar *K*, on the shaft, to bear thereon.

The shaft is supported principally by the collar *K*, while the bearings, above and below, are designed as guides to prevent the displacement of the shaft laterally.

In order to prevent the wear of the metal collar *K*, the block of wood *I* is inserted in the top of the curb, as before stated.

Having thus described my invention, I claim as new, and desire to secure by Letters Patent—

1. The plano-convex gates *E*, arranged in the mouths of the chutes, and geared with the wheel *H*, substantially as specified.

2. The arrangement of the hollow convex bearing *I*, upon the case, or other support, about the wheel, and the concave bearing *K*, substantially as specified.

S. H. BARNES.
